UNITED STATES PATENT OFFICE.

SQUIRE S. TURNER, OF COLUMBIA, MISSOURI.

ENDLESS-CHAIN SICKLE FOR MOWERS AND REAPERS.

SPECIFICATION forming part of Letters Patent No. 323,609, dated August 4, 1885.

Application filed May 26, 1884. (No model.)

To all whom it may concern:

Be it known that I, SQUIRE S. TURNER, of Columbia, in the county of Boone and State of Missouri, have invented a new and useful 5 Improvement in Endless-Chain Sickles for Mowers and Reapers, of which the following is a full, clear, and exact description.

Reference is to be had to the accompanying drawings, forming a part of this specification, 10 in which similar letters of reference indicate corresponding parts in all the figures.

Figure 1 is a plan view of my improvement, part being broken away. Fig. 2 is a sectional front elevation of the same, taken through the 15 line x x , Fig. 1. Fig. 3 is a sectional end elevation of a part of the same. Fig. 4 is a sectional front elevation of a number of sickles. Fig. 5 is a sectional front elevation of a sickle, enlarged, and showing its connecting-link.

20 The object of this invention is to provide mowers and reapers constructed in such a manner as to avoid the wear and tear and loss of power caused by a continuous change of motion.

25 The invention consists in the construction and arrangement of parts, as will be herein-after fully described and specifically claimed.

The endless chain, band, or belt of sickles passes around chain-wheels driven from the 30 drive-wheel of the reaper or mower, one of the said chain-wheels being pivoted to an adjustable crank-axle, so that the tension of the said endless chain of sickles can be readily regulated. The endless chain, band, or belt 35 of sickles is provided with guide-rollers pivoted to adjustable crank-axles, so that the upper and lower parts of the said endless chain of sickles can be kept close together. The upper and lower parts of the endless chain, 40 band, or belt of sickles are separated and covered with guard-plates to protect them from injury and clogging, as will be hereinafter fully described.

A represents the cutter-bar of a reaper or 45 mower, to the inner end of which is secured a pair of standards, B, to and between which is pivoted a chain-wheel, C. To the outer end of the cutter-supporting bar A is secured a pair of standards, D, between which is placed a chain-wheel, E. The chain-wheel E revolves upon a 50 journal of a crank-axle, F, the upright arm of which is slotted to receive the bolt G, by which

the said crank-axle is secured to the rear standard, D, so that the chain-wheel E can have a lateral adjustment to regulate the tension of 55 the endless chain H or a band or belt passing around the chain-wheels C E. The endless chain H is formed of links hinged to each other by small links or rings or other suitable means. 60

To the links of the endless chain H are secured, by rivets or other suitable means, the sickles I, which may be made with smooth or serrated edges, as may be desired.

The upper part of the endless chain H is 65 held close to and parallel with the lower part by guide-rollers J, placed upon the journals of the crank-axles K, the upright arms of which are slotted to receive the bolts L, by means of which the said crank-axles are secured to the 70 adjacent parts of the rear standards, B D, so that the said guide-rollers J can be readily adjusted. The upper and lower parts of the endless chain H are separated by a plate, M, attached to the cutter-bar A, and which I prefer 75 to make with a square forward edge fitting into recesses in the adjacent sides of the sickles to allow the sickles I of the two parts of the chain to come close together. The outer sides of the endless chain H are covered and protected 80 by plates N, attached to the cutter-supporting bar A.

The outer and inner ends of the cutter-supporting bar A are provided with shoes O in the ordinary manner, and the outer end of the 85 said cutter-supporting bar is provided with an ordinary guard, P, to separate the grass or grain.

The rear journal of the inner chain-wheel, C, projects, and revolves in a bearing, Q, attached 90 to the cutter-supporting bar A, and to it is attached a gear-wheel, R, the teeth of which mesh into a gear-wheel, S, connected in the ordinary manner with the drive-wheel of the machine. 95

With this construction the sickles will operate with a continuous movement, the upper and lower sickles moving in opposite directions, so that the grass or grain will be cut between them. 100

With this construction, also, the wear and tear caused by the constant change in the direction of motion will be avoided, so that the machine will be made lighter and will require

much less power to draw and operate it than machines constructed in the ordinary manner.

Having thus described my invention, I claim as new and desire to secure by Letters Patent—

- 5 1. In a reaper or mower, the cutter-bar A, provided at its opposite ends with vertical standards D D B B, in combination with the chain-wheel C, journaled in standards B B, the crank-axle F, provided with a vertical slotted arm, screw G, securing the same adjustably to one standard, D, the endless chain of sickles and guide-rollers, substantially as set forth.
- 10 2. In a reaper or mower, the combination, with the cutter-bar, vertical standards B B D D, the chain-wheels journaled between said standards and the endless chain of sickles, of the crank-axles K K, having vertical slotted arms, screws L, securing them adjustably to one standard, B and D, respectively, and the 15 guide-rollers J J, journaled on said adjustable crank-axles, substantially as set forth.
- 20

3. A reaper or mower having a cutting apparatus comprising the cutter-bar A, standards D D at the outer end and standards B B Q at the inner end; the chain-wheel C, journaled between the standards B B, and having its shaft extended to the bearing Q, the gear-wheel R on said shaft, the chain-wheel E, the crank-axle F, provided with a vertical slotted arm, screw G, securing the same to one standard, D, the crank-axles K, having slotted arms and set-screws, the guide-rollers J J, the central guard-plate, M, the chain of sickles passed around the chain-wheels, and the guard-plates N, substantially as set forth. 25 30
